UNITED STATES PATENT OFFICE.

JOSEPH P. BAUMGARTNER, OF PHILADELPHIA, PENNSYLVANIA.

GARTER ATTACHMENT.

1,278,292.

Specification of Letters Patent. Patented Sept. 10, 1918.

Application filed April 13, 1917. Serial No. 161,772.

To all whom it may concern:

Be it known that I, JOSEPH P. BAUMGARTNER, a citizen of the United States, residing at 3306 N. 15th street, Philadelphia, in the 5 county of Philadelphia and State of Pennsylvania, have invented certain new and useful Garter Attachments, of which the following is a specification.

The purpose of my invention is to provide 10 a garter attachment which shall clasp the stocking resiliently, avoiding tearing of the stocking.

A further purpose of my invention is to distribute the strain upon the stocking be- 15 tween the clasp itself and the front and back faces of the clasp.

A further purpose of my invention is to provide a garter clasp button, circumferentially grooved and of approximately ellipti- 20 cal section, in combination with an elliptical surrounding ring adapted to be turned transversely for gripping position.

A further purpose of my invention is to provide relatively rotatable gripping parts 25 with latching mechanism for holding them in set position, utilizing the resiliency of the fabric support to give "spring" for the latch.

A further purpose of my invention is to provide an adjustment for a garter support 30 that can be freely moved in either direction by thumb-and-finger movement on the front and back thereof.

Further purposes of my invention will appear in the specification and the claims 35 thereof.

I have preferred to illustrate my devices by but one form of each, selecting forms which are practical, efficient and relatively inexpensive and which at the same time well 40 illustrate the principles thereof.

Figure 1 is a front elevation of my invention.

Fig. 2 is an enlarged fragmentary side elevation of Fig. 1.

Fig. 3 is an enlarged fragmentary section of Fig. 1 on lines 3—3 thereof.

Fig. 4 is an enlarged fragmentary front elevation of Fig. 1 with the parts in a different position.

Fig. 5 is a rear elevation of the front portion of my attachment.

Fig. 6 is a broken section upon lines 6—6 of Fig. 5.

Figs. 7 and 9 are perspective views of two 55 variant forms of the front member of my

attachment. Fig. 7^a is a section on line 7^a—7^a in Fig. 7.

Fig. 8 is a front elevation of the movable gripping portion of the front member of my attachment.

Fig. 10 is a front view and Fig. 11 a perspective of the rear member of my attachment.

Fig. 12 is a front elevation of a modified form of the rear member of my attachment.

Fig. 13 is a section of Fig. 12 upon lines 13—13 thereof.

Figs. 14 and 16 are front and rear elevations respectively of my adjustment in position upon a garter support.

Fig. 15 is a broken section upon lines 15—15 of Fig. 14.

Similar numerals of reference indicate like parts in the drawing.

My attachment is intended for use in holding ladies', children's or men's hose, whether supported from a corset, a waist or by an encircling band, and comprises a rear member 20 and a front member 21 with supporting, preferably inextensible, straps 22 and 23 for the two members. These straps are made up, each, of outer cover strips 24, preferably of silk belting on the outside and inside, and inner linings or protective facings 25, preferably of book-binder's webbing cemented thereto for the purpose of preventing raveling and reinforcing the strength.

The rear or button member is shown in Fig. 10 as comprising a base 26 slotted for sewing to the strap 22, and, securely attached thereto, a button 27 of non-circular, preferably elliptical section, for the greater part of its height. The button is circumferentially grooved about the ends at 28 to a diameter substantially the shorter axis of 95 the ellipse.

The front member comprises an outer cover or a guard 29, held to strap 23 by tangs 30, and an oscillatory ring 31 and both non-circularly apertured, as at 32 and 33 to agree with the section of the button, but slightly larger than it.

The tangs by which the front cap is attached, are passed through the fabric of strap 23 and also, for security, through the 105 openings 34 of a washer 35 and clenched within seats 36 depressed with respect to the face of the washer as seen in Figs. 5 and 6.

The cap or guard is thus secured against 110

- its strap 23 with the edge surfaces 37 tightly engaging the fabric, allowing free space between the edge 38 and the fabric sufficient, with slight compression of the material of the strap, to allow passage of the ear 39 upon ring 31. The notches 40 and 41 allow the ear 39 to spring in or to "latch" at each end so as to hold the ring at each extremity of its oscillatory movement.
- 10 The resilience of the fabric here acts as a spring against which the ear must be moved to free from this "latched" position. For convenience in grasping I may use a second ear 39' upon the opposite side of the ring and remove substantially all of the edge at the opposite side, 42 of the cover from edge 38, as at 42' Fig. 9 so as to allow free movement of a second ear. The same notches 40 and 41 are shown here as in Fig. 7.
- 20 In Fig. 12 the rear or button member is shown as mounted upon a base 24' which is provided with reversely bent terminals 44 which may be conveniently notched at 45, and which are adapted to surround a portion or all of the rear strap 22 as may be convenient, preferably entering between the front and rear folds of this strap and being secured in position against longitudinal movement along the strap by threads or other fastenings at 46. The strain against movement perpendicularly from the strap is taken up by the terminals 44, giving additional strength and requiring less sewing than in the form of Fig. 10.
- 30 In operation, the members shown as assembled in Figs. 1, 2, 3 and 4 are separated to allow the stocking 43 to fit between, covering the button. When the outer member is brought to place and the oscillatory ring 31 is turned to secure the parts in the position seen in Fig. 3, the stocking is gripped between the front face 47 of the rear member and the rear face 48 of the front member, as well as between the button and the ring 31. The strain upon the stocking is therefore distributed between that portion gripped by these plane gripping surfaces, by which it is first taken up, and the grip between the button and the ring.
- 40 The construction shown in Figs. 14 and 16 comprises a single piece adjuster for the garter clasp which will find its greatest use presumably in ladies' garters of the character that are attached to a corset or other upper clothing, though capable of use with children's waists and for belts, suspenders and allied uses where quick and safe adjustment are desirable.
- 50 The sheet or the plate from which the adjuster is formed is bent rearwardly and reversely at the edges 49, 50 to form rear terminals 51, 52 between which and the front face a passage 53 is provided for the suspending fabric, which may be firm or elastic as desired.

The front of the adjuster is split up by transverse slots or openings 54, 55 and 56 into front strips 57, 58, 59 and 60. The rear terminals 51 and 52 are nearly opposite strip 57 and rear terminals 62 lie nearly opposite slot 55. Between them lie ears 63 opposite strip 58. That edge of strip 62 adjacent to the lower end of the adjuster is serrated or otherwise roughened at 64 to grip the fabric turned about it when either stretch of the fabric is under tension. The straps 22 and 23 are supported by strip 60.

In assemblage, the main stretch of the fabric is threaded down through the front part of passage 53 between the upper front member 57 and the rear terminals 51, 52, continuing through slot 54, thence downwardly over front strip 58, downwardly and rearwardly through slot 55, about the roughened edge 64 of terminals 62, upwardly in the rear of these terminals, then forwardly to come between ears 63 and front plate 58 and out through the rear part of the passage between front plate 57 and terminals 51, 52. Slide 65 supports the end of the fabric.

It will be noted that an appreciable portion of the fabric is exposed at the front and also in the rear of my adjuster. This is enough in practice for the fabric to be pulled through the adjuster by placing the thumb and forefinger upon opposite exposed portions tightly, and moving the thumb and forefinger toward or from each other to adjust the position of the fabric therein, offering both convenience and speed of adjustment difficult otherwise of attainment. However, strain upon either portion of the fabric draws the fabric against the lower edge of terminals 62, giving a grip which will hold against normal strains and which is rendered reliable and fully effective by teeth upon the lower edge at 64.

It will be evident that my attachment and adjuster coöperate with the fabric to provide the entire equipment for a corset garter and to provide the adjustment and grip for any existing type of garter.

It will be evident that various changes in the construction shown may be made without departing from the spirit and scope of my invention as outlined in the claims hereof; that my gripping mechanism is capable of use in other locations, such as for suspender terminals in "jumper" use; and that the disclosure in connection with the garter is one merely of greatest prospective use and not a limitation thereof.

Having thus described my invention, what I claim as new and desire to secure by Letters Patent is:

1. In a garment clasp, an elliptical button, grooved about the ends of the major axis, a support therefor, an outer member fitting over the button, a ring carried by the outer member and adapted to turn into

the grooves of the button, a fabric with which one face of the ring engages, and retaining means for holding the ring in turned position, taking advantage of the 5 resilience of the fabric.

2. In a garment clasp, a non-circular button grooved about its larger dimension, a base therefor, a flexible support for the base, a cover adapted to fit over the button, a 10 flexible support therefor, tangs on the cover holding it to the flexible support, the cover being spaced from the support throughout a portion of its periphery and additionally spaced at one point, in combination with a 15 ring between the cover and support projecting through the spacing and having greater thickness than the free width of the greater part of the spacing.

3. In a garment clasp, a button of non- 20 circular section, grooved circumferentially about the portion of larger section, a base therefor, a fabric support for the base, a cover adapted to fit over the button, tangs on the cover, a fabric support through 25 which said tangs are adapted to be fastened,

leaving a space between the cover and the fabric between the tangs larger at the ends of the space than between the same, a ring between the cover and support adapted to pass over the button and turn into the 30 groove thereof and means on the ring passing into the space and snapping into the extra space at each end thereof.

4. In a garment clasp, a button of elliptical cross section grooved at the ends at an 35 intermediate point of its height, a base therefor, a flexible support for the base, a cover, a flexible support to which the cover is attached, a ring adapted to pass over the button and to swing between the cover member and flexible support and a projection upon the ring resiliently engaging the flexible support at intermediate positions and adapted to latch in the extremities of its 40 movement by reason of the resilience of the 45 support.

JOSEPH P. BAUMGARTNER.
